UNITED STATES PATENT OFFICE.

JOHN R. HERSH, OF DENVER, COLORADO, ASSIGNOR TO LOUIS E. KENWORTHY, OF SAME PLACE.

ELECTRIC CUT-OUT.

SPECIFICATION forming part of Letters Patent No. 539,583, dated May 21, 1895.

Application filed January 11, 1895. Serial No. 534,516. (No model.)

To all whom it may concern:

Be it known that I, JOHN R. HERSH, a citizen of the United States, residing at Denver, in the county of Arapahoe and State of Colorado, have invented certain new and useful Improvements in Electric Cut-Outs; and I do hereby declare that the following is a full, clear, and exact description of the same, reference being had to the annexed drawings, 5 making a part of this specification, and to the letters of reference marked thereon.

This invention is an improved cut out for electric currents and though particularly adapted for electric cars, can be used in various situations.

The object of my invention is to provide an improved device which will operate by fusing a metallic link or conductor whenever the current reaches a certain strength, and a further 20 object is to provide a cut out comprising a series of such fusible links, so that when one is fused another can be quickly moved in its place, and a still further object is to provide simple but efficient means for moving the 25 fused link out of the way and bringing a new one in connection with the members of the conductor wires.

With these objects in view my invention consists of a case containing a disk carrying 30 a series of fusible links, and contact plates, connected with said links, a brush adapted to engage the contact plate, and connected with one conductor, a conductor plate or plates connected with the other conductor and contacting with the fusible links, means for revolving the disk and an indicator for showing which link of the series is in connection with the conductor wires.

My invention consists also in certain details 35 of construction and combination of parts all of which will be fully described and then pointed out in the claims.

In the drawings forming a part of this specification, Figure 1 is a front view of my 40 improved cut-out, part of the case being broken away to show the interior mechanism. Fig. 2 is a central vertical section. Fig. 3 is a rear face view of the rotating disk. Fig. 4 is a face view of the rear section of the case, and 45 Fig. 5 is a detail view of the operating-lever.

In carrying out my invention I employ, a

circular case A, composed of the front section a and rear section b said sections being connected by bolts c. Binding posts B B are arranged upon the front section and to which 55 the wire C C are connected. A conductor wire D extends from one post into the interior of the case and carries a brush E at its inner end composed of a series of thin metallic plates, and connected with the other post is a 60 conductor wire F which extends into a hub f and connects with a conductor plate G carried upon the inner face of said hub.

Mounted within the case A and adapted to rotate therein is a disk H, having journals h 65 projecting from each face and which bear in the front and rear sections of the case. A series of contact plates K are secured about the periphery of the disk and connecting with each contact plate is a link L of fusible metal, said links being arranged radially, and have their inner ends secured between two metallic plates M, said plates contacting with the conductor plates G and thus establishing a connection between the contact plate 70 K and the conductor wire F and as the brush E contacts with the plate K, a complete connection is made between the two sections of the main wire C. The connection being thus established the current will pass from the 75 brush to the contact plates, thence along the link L to the plate M and then to the plate G and conductor wire F to the wire C. This will continue until the current becomes so strong as to fuse, the metallic link L when 80 the current will be interrupted or cut out and will remain so until another plate is brought into contact with the brush. In order to do this I form the rear face of the disk H with a series of ratchet teeth N and pivot upon the 85 rear journal h a lever O carrying a spring pawl P which is adapted to engage the ratchet teeth of the disk and rotate the same step by step as the lever is moved. This lever O projects outward between the sections of the case 90 and connected with its outer end is a cord o by means of which the operator can work the lever and bring a new plate into contact with the brush. The pawl P is held in close contact with the ratchet faced disk by means of 95 a presser plate p secured upon the inner face of the rear section b and this plate also 100

serves to press the disk forward and hold the plate M in contact with the plate G.

In order to hold the disk H in position while the lever is being retracted to bring the pawl 5 into contact with another tooth I employ a locking pawl q, which is secured to the rear section of the case, and to return the lever to its normal position I provide a coiled spring R arranged in a groove r produced in the faces 10 of sections a and b said spring being connected with the lever at one end and to a pin s at the other end so that the moment the tension is released from the cord o the spring will return the lever to its normal position, shown 15 in Fig. 1 and the movements of said lever are limited by the extent of the opening in the case through which it projects.

Now when one of the links becomes fused and it is desired to re-establish the current 20 the lever O is drawn up by cord o bringing the next plate K to the left into contact with the brush E and this operation can be repeated as long as there are fusible links left to bring into contact.

25 To indicate which link is in contact, I mount an indicator finger T upon the outer end of the forward journal h and place a dial V upon the front face of the case containing as many numerals as there are links to be 30 used and in this case I have shown XV. When all the fusible links are good, the indicator will point to the numeral XV showing that fifteen links can be used and when the first one becomes burned out and the next 35 one is brought into contact the indicator moves to the left to the numeral XIV showing that fourteen links are left. The operations thus described can be continued until all the links have been used when the cut out 40 is disconnected and a new one substituted or new links put in the same one.

This device is usually arranged in a vertical position as shown in Fig. 1 and can be fixed at any convenient place about the car.

Having thus described my invention, what 45 I claim is—

1. In an electric cut out the combination with a case having conductor wires connected therewith, of a disk mounted to rotate therein, said disk having a series of fusible metallic 50 links upon one face, and a series of ratchet teeth upon the other, the lever and pawl and means for connecting the fusible links with the conductor wires, substantially as shown and described.

2. The combination with a case having a dial upon the outer face of a disk arranged within the case, the conductor wires and plates, the fusible wires and contact plates, the brush, the operating lever and pawl and returning spring, the presser plate, and indicator all arranged substantially as shown and described.

3. In an electric cut out, the combination with a case, made in two sections, of a disk 65 journaled therein, and having a series of ratchet teeth upon one face, the operating lever carrying a pawl for engaging said teeth, the presser plate and locking pawl, the contact plates and fusible links carried upon the 70 opposite side of the disk, the conductor wires leading into the case, one of them connected with the contact plates, the other carrying a contact brush, all of said parts being arranged, substantially as shown and described.

In testimony that I claim the above I have hereunto subscribed my name in the presence of two witnesses.

JOHN R. HERSH.
